UNITED STATES PATENT OFFICE.

THEODORE KOCH, OF MILWAUKEE, WISCONSIN.

WASTE-PIPE TOOL.

No. 874,512.

Specification of Letters Patent.

Patented Dec. 24, 1907.

Application filed June 22, 1906. Serial No. 322,915.

To all whom it may concern:

Be it known that I, THEODORE KOCH, of No. 515 Western avenue, Milwaukee, Wisconsin, citizen of the United States, residing 5 at Milwaukee, in the county of Milwaukee and State of Wisconsin, have invented certain new and useful Improvements in Waste-Pipe Tools, of which the following is a specification.

10 This invention relates to improvements in tools for removing obstructions in sewer pipes, cisterns and other places where it is desirable or necessary to remove obstructions and which are inaccessible except for 15 tools of comparatively small cross diameter and considerable length.

The especial object of the improvements which form the subject matter of this application is to provide a tool that may be inserted 20 in a drain pipe, cistern or the like, which may be used in grasping and withdrawing obstructions placed in such pipes and which may be provided with lighting devices so that the obstructions may be 25 seen by the operator while using the tool. Having these and other objects of general utility in view I have invented the device hereinafter described in detail and shown in the accompanying drawings, in which:—

30 Figure 1 is a side elevation of the tool, and Fig. 2 is a rear elevation of the same tool in its inverted position.

Referring to the details of the drawing, 3 represents a wood staff or bar which may be 35 of any suitable length and thickness. Secured to one end of this staff by screws 5, is a clasp composed of the back piece 4, and the clamping member 6 mounted on the back piece by pivot 7, and held under tension by 40 the flat spring 8 one end of which is secured to one end of the staff. To the upper end 11 of the clamping member is secured a chain 9 which travels over a pulley 12 mounted in a suitable recess provided therefor in the staff.

45 The upper end of the chain is secured to a staple 10 which is fixed in one side of the staff. Secured to the side of the staff by screws 16 is a flat metal plate 15 to one end

of which is secured a socket 13 adapted to receive a candle 14. A similar plate 15 and 50 socket 13 are secured at the opposite end of the staff and at this end, a hook 17 is secured by bolts 18.

To use a tool constructed substantially as described, the end of the staff on which 55 the clamp is mounted, is lowered into the pipe or cistern or other place from which it is desired to remove obstructions and if necessary, the candle 14 is lighted so that the operator can see the obstruction and then by 60 pulling upwardly on the chain 9 open the clamping end of the member 6, and thus grasp the obstruction, which is withdrawn by raising the staff. If the obstruction is of such a nature as to be removable by the 65 hook 17, the end of the staff containing said hook is used instead of the clamp.

It will be apparent that various modifications in detail may be made in this device such as changes in the form of the clamp 70 utilized, but any such modifications are matters of mere mechanics and do not affect the principles of my invention which it is desired to cover in the patent hereby applied for.

Having thus described my invention what I claim, is:—

1. A tool consisting of a staff, a hook secured at one end of said staff, a spring-held clamping device secured at the opposite end 80 of said staff, and means for releasing said clamping device, said means comprising a chain and a pulley on said staff.

2. A tool consisting of a staff, a spring-held clamping device secured at one end of said staff, means for operating said clamping device, a hook secured to the opposite end of said staff, and means for providing illumination adjacent to said hook and clamping device respectively for the purpose described. 90

In testimony whereof I affix my signature in presence of two witnesses.

THEODORE KOCH.
